UNITED STATES PATENT OFFICE.

SAM EVERETT FINLEY, OF ATLANTA, GEORGIA.

METHOD OF MAKING ROADWAYS.

Application filed December 15, 1924. Serial No. 755,986.

To all whom it may concern:

Be it known that I, SAM E. FINLEY, a citizen of the United States, residing at Atlanta, in the county of Fulton and State of Georgia, have invented certain new and useful Improvements in Methods of Making Roadways; and I do hereby declare the following to be a full, clear, and exact description of the invention, such as will enable others skilled in the art to which it appertains to make and use the same.

The invention relates to a novel method of constructing roadways and the like of bituminous cement-aggregate concrete and has for its object the production of a road structure of uniform texture, density, durability and imperviousness to weather conditions, at a minimum cost. To this end, the invention comprises spreading the mineral aggregate, of proper character, upon the prepared subgrade of the roadway in a uniform layer between edge defining forms placed temporarily in series longitudinally of the roadway, compacting the aggregate, preferably by rolling, removing the forms along one edge of the compacted mineral aggregate layer, applying a coat of bituminous binding medium to the longitudinal section of the roadway adjacent said edge and to the vertical face of the aggregate layer constituting said edge, then, preferably, finishing the coated longitudinal strip by the application of the usual casting of stone chips, removing the forms on the opposite side of the aggregate layer and similarly treating the adjacent longitudinal section by the application of a coating of the binding medium to the top surface and the lateral face or the vertical edge, and ultimately finishing the coated longitudinal section, as in the first instance. The invention is illustrated in the accompanying drawings, in which:

Fig. 1 is a transverse section of a roadway under construction, showing the application of loose broken stone between the removable shoulder forms.

Fig. 2 is a similar view showing the construction after the aggregate layer has been rolled.

Fig. 3 is a similar section illustrating the mode of applying the binding medium to the surface and shoulder or vertical edge of one longitudinal section of the compacted layer of aggregate.

Fig. 4 is a similar section showing the completed roadway.

Fig. 5 is a fragmentary perspective view of a spray header adapted to apply the binding medium.

In the construction of roadways, involving the application of layers of broken stone or other mineral aggregates on suitably prepared foundations or subgrades, prior to the application of the binding medium to the aggregate, it has been customary to lay temporary forms longitudinally of each side of the roadway to define the marginal edges of the aggregate layer, the forms being retained in position until after the aggregate has received an application of binding medium. It has been regarded as necessary to permit the edge defining forms to remain in position, in order to prevent the mineral aggregate from raveling out at the edges during the rolling operation, prior to the application of the binding medium, the forms serving to maintain the proper cross section and contour of the aggregate layer. The inherent objection to this practice is the fact that the binding medium, which is highly ductile and adhesive, will adhere to the forms as well as the aggregate, and when it is attempted to remove the forms, the portions of the aggregate which are adhesively attached to the forms by the binding medium will be pulled out of the body of the aggregate layer, thereby impairing the latter and rendering it necessary to replace the displaced material, both the aggregate and the binding medium, which operation involves considerable expense and trouble. Furthermore, when the edge defining forms are permitted to remain in position, until the road surface is finished, in the operation of applying the finishing coat of stone chips, it is practically impossible to keep some of the chips from falling on the tops of the forms and, when the roller in the final compacting operation comes in contact with these chips, the latter will prevent a uniform compression of the road structure by the roller, as the wheels or the drums of the latter will be prevented from maintaining a uniform contact with the road surface by the stones on the tops of the forms, so that the road surface is impaired and the concrete body will necessarily be of non-uniform density, compactness and cross section.

The instant invention is effective in avoiding the difficulties and objections inherent in the former practice and enables thoroughly homogeneous and uniformly compacted layers of concrete to be applied to the road under conditions that will insure the maintenance of the proper cross section of the cemented body of aggregate, with sharply defined vertical lateral edges, which 10 may, if desired, be fashioned to constitute integral headers or curbs by the application of an additional quantity of binding medium to the edge sections.

The mode of procedure is clearly illustrated in the drawings in which 1 represents the site of the roadway or equivalent structure, which is worked to proper grade and contour to receive the concrete. Placed in two parallel rows and running longitudinally of the roadway are edge defining forms 2—2, which may be of wood or other suitable material, preferably having a thickness equal to that of the initial concrete slab, the forms being fixed or anchored in position by any suitable means, but being readily removed. Between the forms, which are spaced apart a distance equal to the width of the roadway, is spread a layer of broken stone, or other suitable mineral aggregate, of proper grades and sizes, the top surface of the layer being preferably worked to an approximate contour. This layer of broken stone confined between the forms 2—2 is then thoroughly rolled to compact 30 the same and to effect a substantial mechanical bond between the various elements of the aggregate, as illustrated in Fig. 2. The compacted layer of aggregate is self-supporting, so that, when the forms 2 on the 40 right-hand side of the road, for example, as illustrated in Fig. 3, have been removed, the vertical lateral edge of the layer of broken stone will remain intact. After the right-hand forms have been removed, a suitable 45 binding medium, preferably in the form of highly heated stable bitumen or asphalt, is applied to the right-hand section of the mineral aggregate layer, by the method and apparatus for treating roadways disclosed in my prior Patent No. 1,341,458, dated May 25, 1920, the apparatus involving a tank wagon, such as 10, having a laterally disposed spray header 11 adapted to distribute the binding medium uniformly over the 50 surface of the right-hand section of the layer of mineral aggregate, the spray header also being provided with one or more terminal or end spray nozzles 13, so constructed and arranged as to deliver the binding medium 55 against the vertical lateral face of the layer of aggregate. Preferably, multiple nozzles 13 are used to supply an additional quantity of asphalt to the lateral edge and vertical 60 face of the aggregate layer, thereby producing what is, in effect, an integral header or

curbing along the edge of the roadway. While the application of the binding medium to the right-hand longitudinal section of the aggregate layer is being effected, the vehicle traverses the left-hand untreated section of the aggregate layer, and in order to prevent the aggregate being displaced laterally by the passage of the vehicle, the left-hand forms 2 are retained in position. After the right-hand section has been treated with binding medium, as described, any desired form of surface treatment or finish may be applied, such, for example, as the customary casting of stone chips, with or without the application of a seal coat of 70 binding medium, as conditions may require, the left-hand longitudinal section of the aggregate layer is reworked, if necessary, to remove the ruts or other impairments produced by the wheels of the tank wagon, and 75 the latter is then traversed over the wholly or partially finished right-hand section of the roadway to distribute the binding medium to the left-hand section of the roadway, coating the surface and the lateral edge 80 or shoulder of the aggregate layer as in the first instance, the forms 2 along the left-hand edge of the aggregate also having been removed prior to the application of the binding medium. The left-hand section is 85 then finished in the same manner as the right-hand section and, if necessary or desirable, the entire surface of the road is re-rolled to bring it to uniform grade and contour, after which earth or other suitable 90 material may be deposited laterally of the paved surface on both sides and finished to the desired contour, or, if preferred, permanent headers or gutters bounding the lateral edges of the roadway may be constructed. 95

What I claim is:

1. The method of constructing roadways comprising placing edge defining forms longitudinally of the road site, spreading mineral aggregate between the forms to the desired depth, compacting the aggregate, removing the forms along the edges, and applying a coating of binding medium to the surface and to the vertical edges of the aggregate layer. 110

2. The method of constructing roadways comprising placing edge defining forms longitudinally of the road site, spreading mineral aggregate between the forms to the desired depth, compacting the aggregate, removing the forms along one edge, applying a coating of binding medium to the adjacent longitudinal section of the surface and to the vertical edge of the aggregate layer, then removing the forms along the other edge, and similarly treating the surface of the adjacent section and the latter edge. 120

3. The method of constructing roadways comprising placing edge defining forms lon- 125

- 5 longitudinally of the road site, spreading mineral aggregate between the forms to the desired depth, compacting the aggregate, removing the forms along one edge, applying a coating of binding medium to the adjacent longitudinal section of the surface and to the vertical edge of the aggregate layer, finishing the coated section, then removing the forms along the other edge,
- 10 10 similarly treating the surface of the adjacent section and the latter edge, and finally finishing the second coated section.

4. The method of constructing roadways

comprising placing edge defining forms longitudinally of the road site, spreading 15 mineral aggregate between the forms to the desired depth, compacting the aggregate, removing the forms along the edges, applying a coating of binding medium to the surface of the aggregate layer and an excess 20 quantity of binding medium to the vertical edges of said layer.

In testimony whereof I affix my signature.

SAM EVERETT FINLEY.
